UNITED STATES PATENT OFFICE.

AARON THOMAS BINKERD, OF ALLEGHENY, ASSIGNOR TO DUNCAN C. WHITE,
OF PITTSBURG, PENNSYLVANIA.

GAGE-CHISEL FOR CUTTING HINGE-RECESSES.

SPECIFICATION forming part of Letters Patent No. 393,880, dated December 4, 1888.

Application filed March 16, 1888. Serial No. 267,331. (No model.)

To all whom it may concern:

Be it known that I, AARON THOMAS BINKERD, of Allegheny, in the county of Allegheny and State of Pennsylvania, have invented a new and Improved Gage-Chisel for Cutting Hinge-Recesses, of which the following is a full, clear, and exact description.

My invention relates to a tool adapted more particularly for scoring or cutting recesses to receive the leaves of butt or other hinges, and has for its object to provide a simple, inexpensive, and efficient tool of this class, by the aid of which hinges of any size may be quickly, easily, and neatly set into work and without the aid of compass, try-square, or ordinary marking-gages.

The invention consists in certain novel features of construction and combinations of parts of the gage-chisel, all as hereinafter described and claimed.

Reference is to be had to the accompanying drawings, forming a part of this specification, in which similar letters of reference indicate corresponding parts in all the figures.

Figure 1 is a side elevation of my improved gage-chisel, and shows also a portion of the edge of a door or other structure into which recesses are to be cut by the chisel to receive hinges. Fig. 2 is a view taken at right angles to Fig. 1 and with the chisel-head partly broken away and in section, and Fig. 3 is a view of the tool at its cutting-face.

The gage-chisel is made with a metal stock, A, having a square or rectangular lower or outer end portion or head, a, to which the cutters are fixed, as presently explained, and is provided with a suitable handle, B, affording a firm grasp of the tool by one hand while the handle is struck by a hammer in operating the tool.

The chisel-cutters C D E are held by screws c d e, respectively, to three sides or faces of the stock-head a, and so that their cutting-edges, which are sharpened from the inner faces of the cutters, stand at right angles to each other and in the same plane, and with one mitered or beveled side edge of the cutters D E meeting the opposite mitered or beveled side edges of the cutter C in a manner to cause the tool to make a clean cut or incision

having an angular or rectangular outline as it is forced or pressed to the work. Washer-plates or washers c' d' e' may be used under the heads of the screws c d e, if preferred.

In the end of the stock-head a, and within the square or space formed between or within the cutters C D E, is fitted a screw, F, which may be turned in or out, so that its head or outer end, f, serves as a stop to gage the working depth of the cutters. The same screws d e which hold the cutters D E to the tool-stock head also hold to the outer faces of said cutters two gage-plates, G G, which have slots g, through which the screws pass to allow the lugs H H of the gage-plates to be set so that their gaging faces or shoulders h h stand the required distance back of the face of the chisel-cutter C, and these gage-plates G are preferably provided with a graduated scale, I, by which the plates may be placed with reference to a fixed mark or index-line, J, on the tool-stock to allow the gage-plates to be set accurately without using a rule or other measure for the purpose.

In using this tool the gage-plates G will be set so that their shoulders h will stand at the same distance from the outer face of the cutter C as the butt or other hinge is to be inserted edgewise into the door K from the door-face k, and the screw F will be set back from the sharp edges of the cutters a distance equaling the thickness of the leaf of the hinge. The hinge will now be laid onto the door and two marks will be made—one at each end of the hinge—and one of the cutters, D or E, will be held at one of these marks, while the gage-plate shoulders h are held to the face k of the door, and the tool will be struck a sharp blow or pressed into the wood as far as the gage-screw F will allow, and then will be lifted and set along toward the other end mark of the hinge a little distance, and will be again struck into the wood, and so on until all the wood which is to be removed to form the hinge-recess is scored or cut, and the cutter D or E opposite the one used at the first end mark of the hinge will be set at the other end mark, whereupon the final blow or pressure will be given the tool, and the wood which had been cut or scored by the tool, as above described,

will be removed easily in chips by an ordinary chisel to completely form the hinge-leaf recess.

This hinge-recess cutting-tool may be used to advantage for cutting the hinge-recesses on the fixed jamb or casing, as well as on the door or other swinging structure to be hung thereto.

The two gage-plates G G may be connected by a cross-bar, G', (indicated in dotted lines 10 in Fig. 3 of the drawings,) and thus be made in one piece instead of in two separate plates, as will readily be understood.

Having thus described my invention, what I claim as new, and desire to secure by Letters Patent, is—

1. A gage-chisel made with a stock, a cutter or cutters held thereto and making an angular score or incision, a plate or plates held to the stock to gage the working of the cutters laterally, and a set-screw fitted to the stock and within the angle described by the cutters and to gage their working depth, substantially as herein set forth.

2. A gage-chisel made with a stock, a cutter or cutters held thereto and making an angular score or incision, a plate or plates held adjustably to the stock to gage for any required lateral working of the cutters, and a set-screw fitted to the stock and within the angle described by the cutters and to gage their working depth, substantially as herein set forth.

3. The combination, in a gage-chisel, of a stock, A, having a squared head, a, cutters C D E, held to three sides of the head, a gage-screw, F, at the end of the stock and between the cutters, and a gage plate or plates, G, held adjustably to the stock and provided with a shoulder, h, all constructed and arranged for operation substantially as herein set forth.

AARON THOMAS BINKERD.
